UNITED STATES PATENT OFFICE.

ISAIAH CONRAD, OF PHILADELPHIA, PENNSYLVANIA.

STROP FOR RAZOR-BLADES.

939,219.

Specification of Letters Patent.

Patented Nov. 9, 1909.

Application filed August 11, 1909. Serial No. 512,307.

To all whom it may concern:

Be it known that I, ISAIAH CONRAD, a citizen of the United States, residing at Philadelphia, in the county of Philadelphia and State of Pennsylvania, have invented certain new and useful Improvements in Strops for Razor-Blades, of which the following is a specification.

My invention relates to improvements in strops for razor blades, the object of the invention being to provide improved strop holding plates normally held apart by a spring and adapted to be pressed toward each other to clamp a razor blade between them and when drawn off the edge of the blade effectually strop the same.

With this and other objects in view, the invention consists in certain novel features of construction and combinations and arrangements of parts as will be more fully hereinafter described and pointed out in the claims.

In the accompanying drawings, Figure 1, is a perspective view illustrating the application of my improved device in the act of being drawn off a razor blade. Fig. 2, is a view in longitudinal section illustrating the normal position of the device. Fig. 3, is a plan view of the device. Fig. 4, is a plan view of one of the jaws, and Fig. 5, is a view similar to Fig. 1 illustrating a modification.

1, 1, represents two jaws, each comprising a metal plate having inwardly turned edges or flanges 2 to bind against the beveled edge of strops 3, and rivets 4, countersunk in the strops 3, are projected through its jaws and assist in holding the strops firmly in the jaws. The inner ends of the jaws are bent in the general compound curvature shown forming inwardly bent portions 5 having openings 6, to receive a staple 7, having its ends bent at right angles and flat against a jaw. This inwardly bent portion 5 serves as a fulcrum for the hinged movement of the jaws and the staple 7, serves to lock the jaws together. In rear of inwardly bent portions 5, the jaws bend outwardly, as shown at 8, and are provided with slots 9, in their ends, to receive tongues 10 at the edges of a cylindrical spring 11, to hold the latter in engagement with the jaws, and the extreme ends of the jaws are bent toward each other as shown at 12 to engage each other and limit the opening movement of the jaws as shown in Fig. 2.

In operation the operator grasps the jaws 1, 1, between his thumb and fore finger and holding the razor blade with the other hand, presses the strops 3 against opposite sides of the razor and draws them off the edge of the razor. When pressure is relieved, spring 11 will open the jaws ready to again receive the blade and by repeating this operation, blades 13 such as commonly used on safety razors can be most effectually sharpened. 65

In the modification shown in Fig. 5, the jaws 14 and spring 15, are integral.

Various other changes might be made in the general form and arrangement of the parts described without departing from my invention and hence I would have it understood that I do not restrict myself to the precise details set forth but consider myself at liberty to make such changes and alterations as fairly fall within the spirit and scope of the appended claims. 75

Having thus described my invention what I claim as new and desire to secure by Letters Patent is:—

1. As an article of manufacture, a razor 80 strop, comprising jaws, strops fixed to the inner faces of both jaws, and a spring connecting the jaws normally holding them in open position at an angle to each other.

2. As an article of manufacture, a razor 85 strop, comprising two metal jaws having inwardly turned edges, strops secured to the inner faces of said jaws between the inwardly turned edges, means hinging the inner ends of said jaws together and a spring 90 engaging the inner ends of said jaws and normally holding them apart at an angle to each other.

3. As an article of manufacture, a razor strop comprising two metal jaws, strops secured to the inner faces of said jaws, the inner ends of said jaws bent substantially as shown, a staple hinging said jaws together, a cylindrical spring engaging the inner ends of said jaws and normally holding them 100 apart at an angle to each other, and the inner end of said jaws bent forming stops limiting the opening movement of the jaws. 95

In testimony whereof I have signed my name to this specification in the presence of 105 two subscribing witnesses.

ISAIAH CONRAD.

Witnesses:

GEORGE CONRAD,
J. A. L. MULHALL.
